UNITED STATES PATENT OFFICE.

JOHN W. THOMAS AND MERTON A. DIMMITT, OF KOKOMO, INDIANA.

WINDOW-SHADE FASTENER.

1,070,207.

Specification of Letters Patent. Patented Aug. 12, 1913.

Application filed December 20, 1910. Serial No. 598,279.

To all whom it may concern:

Be it known that we, JOHN W. THOMAS and MERTON A. DIMMITT, citizens of the United States, residing at Kokomo, in the 5 county of Howard and State of Indiana, have invented new and useful Improvements in Window-Shade Fasteners, of which the following is a specification.

This invention relates to window shade 10 fasteners, and its object is to provide a light, durable and inexpensive device of this kind which can be readily applied to a window casing without the use of screws, nails or other fastening means which would, 15 of a necessity, mar the facing of the casing.

A further object of the invention is to provide a device of this kind with a longitudinally adjustable bracket, the said bracket adapted to support both the curtain 20 roller and the shade roller, and the said bracket being provided with means whereby the same adjusts and locks the bracket in its adjusted position.

With the above and other objects in view, 25 which will appear as the description progresses, the invention consists of certain novel features of construction and combination of parts which will be hereinafter more fully described and pointed out in the claim.

30 In the accompanying drawings there has been illustrated the preferred form of the invention.

In the said drawings, Figure 1 is a front elevation of the fastener showing the positions of the parts before fastening to a window casing. Fig. 2 is a top plan view of the same showing the fastener secured to the casing. Fig. 3 is a perspective view of one of the members forming the body of the 40 fastener. Fig. 4 is a similar view of the opposite member and the connections therefor. Fig. 5 is a perspective view of one of the sliding brackets. Fig. 6 is a central longitudinal sectional view taken through the 45 device when in its applied position upon a casing.

In the accompanying drawings the numeral 1 designates an ordinary window casing and 2 the window shade fastener adapted 50 to be secured to the casing. The fastener 2 comprises essentially a pair of sections or members designated respectively by the numerals 3 and 4. Each of the members 3 and 4 is preferably formed of a strip of suitable metal and each of the said members 55 is formed with enlarged faces 5 positioned

adjacent their ends. The ends of the said members are bent at right angles to the body portions thereof, as designated by the numeral 6 and the extremities of the bent portions are formed with teeth 7, the latter being adapted to engage the side edges of the vertical members of the casing when the fastener is positioned thereon. Both of the enlarged ends or faces 5 of each of the sections 3 and 4 are constructed in a similar manner and the reference characters referring to one of the said members may be taken as equally applicable to the second member.

The enlargement 5 is formed with longitudinally extending substantially U-shaped slits and the metal provided by said slits is bent outwardly to provide the oppositely arranged, preferably inclined walls 8 and 9. 75 These walls are arranged in a spaced parallel plane to each other, as clearly illustrated in the several figures of the drawing. The enlargements 5 are formed adjacent the transverse edges of the walls 8 and 9 and 80 preferably central of the said edges with smaller substantially U-shaped slits. The metal between these smaller slits is bent outwardly to provide ears 10 and 11. The ears 10 and 11 are arranged at a direct 85 right angle to the walls 8 and 9, and the space between the ears and the walls, which we will refer to as a compartment 12, is adapted for the reception of the longitudinally adjustable bracket 13.

The walls 8 and 9 are preferably inclined 90 toward each other, and the longitudinal edges 14 and 15 of the bracket 13 are likewise inclined so as to snugly engage the inner faces of the said walls. The body of 95 the bracket 13 is straight and adapted to snugly engage within the compartment 12. The outer face of the bracket 13 is centrally provided with a longitudinally extending threaded bore 16, and the ears 10 and 11 are 100 each provided with apertures 17 and 18. The apertures of the ears are adapted to register with the threaded bore 16 of the bracket and the numeral 19 designates a threaded headed member which is adapted 105 to engage both the apertures of the ears and the threaded bore of the bracket. The headed portion of the element 19, when turned, will slide the bracket 13 toward either of the ears 10 or 11 and thereby adjust the said 110 bracket longitudinally of the members 3 and 4 and as the bracket cannot be slid until

the said member 19 is rotated, it will be noted that the said bracket is effectively locked when once properly adjusted.

The reduced longitudinally extending portion 20 of the member 2 has its edges bent upon the body thereof as at 21 and 22 to provide a passage for a bar 23. The outer extremity of the portion 20 is formed with oppositely arranged ears 24, the same being 10 provided with suitable perforations adapted for the reception of a pintle 25, whereby the cam head 26 of a lever 27 is secured. The cam 26 is adapted to contact with the bar 23 so as to retain the same within the 15 passage provided by the inwardly bent portions 21 and 22, to retain the said bar in a longitudinally adjusted position. The extremity of the member 23 is pivotally connected with a lever 28, and this lever has 20 its lower portion extending below its pivotal connection with the bar 23 and said extension is pivoted as at 29 to the longitudinally extending reduced member 30 of the section 4 of the fixture.

25 In positioning the fixture upon a casing the bar 23, being released by the cam 26, is free to slide within the passage of the section or member 3. The offsets 6 of each 30 of the members have their teeth 7 contact the sides of the casing. The lever 28 is then swung upon its pivot 29 causing the bar 23, which is now rigidly connected with the member 3 by the rotation of the cam 26 in an opposite direction, to be drawn toward 35 the extension 30 of the member 4. The lever 28 is securely retained upon the extension 30 through the medium of a suitable catch 31, and the operation of the lever firmly embraces the teeth 4 within the sides of the 40 casing and retains the fastener thereon.

Each of the brackets 13 is provided adjacent its outer end with spaced ears 32, the same being provided with suitable openings which are adapted for the reception of the 45 offset extremities of a wire curtain pole sus-

taining element 33. The inner ends of each of the bracket members are preferably integrally formed with angular offsets 34, one of the same being formed with an annular opening while the opposite member is formed with a rectangular opening, and these openings are adapted to receive the fixtures upon the opposite ends of a shade bracket.

When the fixture has been positioned as above described, it will be noted that the 55 manipulation of the threaded elements 19 will cause the brackets 13 to travel within their compartments 12 in either direction so that different lengths of shades or curtain poles may be readily dispensed with. 60

Having thus fully described the invention, what we claim as new is:—

A fixture comprising a pair of longitudinally adjustable members, the outer ends of said members being enlarged, shade supporting means carried by and secured to said enlargement, the opposite ends of said members being reduced, the reduced portion of one of said members having its longitudinal edges bent inwardly and thence downwardly 70 to form a passage-way, a bar mounted for sliding movement in said passage-way, means carried at the forward end of said passage-way for locking the bar therein, means pivotally connected to the terminal 75 of the reduced portion of the other of said members and to the free terminal of said bar for forcing the members toward each other, the pivotal connection of the bar with the latter mentioned means being at a point 80 directly above the point of pivotal connection of the latter with the latter mentioned reduced member.

In testimony whereof we affix our signatures in presence of two witnesses.

JOHN W. THOMAS.
MERTON A. DIMMITT.
